Primary Examiner — Lauren R Calve(74) *Attorney, Agent, or Firm* — McDonnell Boehnen Hulbert & Berghoff LLP(57) **CLAIM**

The ornamental design of a clamshell package for a cartridge valve, as shown and described.

DESCRIPTION

FIG. 1 is a perspective view of a clamshell package in an open state showing the new design;

FIG. 2 a front elevational view thereof, wherein a rear elevational view is a mirror image of the front elevational view

FIG. 3 is a right side view thereof, wherein a left side view is a mirror image of the right side view

FIG. 4 is a top view thereof, wherein a bottom view is a mirror image of the top view; and,

FIG. 5 is a perspective view of the clamshell package in a closed state.
